atty.

UNITED STATES PATENT OFFICE.

FREDERICK M. DURKEE, OF BROOKLINE, MASSACHUSETTS.

MEANS FOR APPLYING SEALING WAX.

Application filed January 10, 1927. Serial No. 160,189.

My invention relates to means for handling or applying sealing wax and it has for its object to provide improved means through the use of which a wax seal can be applied to a document, envelope or the like with accuracy, neatness and dispatch, and in a manner that is much more secure than has been possible with the means and methods heretofore employed.

10 To these ends my invention consists of seal applying means comprising a body or frame carrying an electric heater whose heating unit may be constructed after the fashion of the well known electric cigar 5 lighter, and a seal or the like which, in the best form of my invention, is also carried by said frame. In using this apparatus a pellet of wax is placed upon the envelope or the like to which the seal is to be applied 15 and after closing the circuit through the electric heater the latter is held in close proximity to the wax pellet resting upon the envelope or the like, so that not only is the wax melted but the paper on which the 20 wax rests is also heated thus establishing and assuring perfect adhesion of the wax to the paper. As soon as the wax is melted 25 the seal is pressed against the melted wax pellet and as soon as the wax hardens the 30 seal is removed. In order to control the circuit of the electric heater, a suitable switch may be provided in the circuit thereof, said switch being preferably mounted on the frame and adapted to be held closed 35 by the hand of the operator which grasps the frame while using the apparatus.

Other objects and features of my invention are hereinafter pointed out.

In the accompanying drawings:

40 Figure 1 is a side elevation of my new seal applying instrument.

Figure 2 is an end view of the instrument shown in Fig. 1.

Figure 3 is a side elevation of the electric 45 heating plug, hereinafter described.

Figure 4 is a detail of a portion of the instrument shown in Fig. 1.

Figure 5 is a plan view of the wax bar hereinafter described.

50 Figure 6 is a side elevation of the wax bar shown in Fig. 5.

Figure 7 is an end elevation of the wax bar shown in Figs. 5 and 6.

Figure 8 is a side elevation, and

55 Figure 9 is a plan view of an individual pellet of wax, described later.

Having reference to the drawings 1 represents a handle frame made at one end with a lateral extension or leg 2 whose free end is made hollow to provide a compartment 3 for holding a number of wax pellets. One wall of this compartment is constituted in part by a door 4 slidably connected with the extension 2, the door being held frictionally in its closed position. At the 65 opposite side of the handle body 1 is provided another lateral extension or leg 7. The two legs 2 and 7 are adapted to support the handle frame 1 in an upright position upon a table or other support when 70 the device is not in use.

Projecting from one side of the handle frame 1, and intermediate the ends thereof, is a seal 8 provided at its outer end with a die surface 9 of usual and desired construction and design. At the end of the handle body 1, opposite the legs 2 and 7, is provided a laterally projecting extension 10 formed at its outer end with a socket of usual construction to receive, with provision 80 for removal, an electric heating unit 11, shown by itself in Fig. 3. The end and shell terminals of the heating unit 11, when the latter is within the socket 10, contact with the center and shell terminals of the 85 latter, and the terminals of the socket are, as in the case of the ordinary electric cigar lighter, arranged within a circuit that includes wires 12, a push-button switch 13 and a screw plug 14. The screw plug 14 90 is adapted to be screwed into the usual lamp socket of a lighting circuit. The push-button switch 13 is also of ordinary construction.

The body 1 may be made hollow, or chambered, to receive the wires 12 and the usual contact members of the push-button switch 13 whose button extends through a hole in the side wall of the handle frame 1 to the exterior of the latter so that it may be controlled and operated by the hand of the person using the instrument. The wires 12 extend into the hollow handle frame 1 and are connected, as usual, with the contacts of switch 13 and socket 10.

As shown in Figs. 1 and 4, the socket 10 is made with two legs or props 15 whose outer ends connect with a circular wall 15⁴ surrounding the outer end of the heating unit and the inner end of this wall is approximately in the same plane with the outer end of the heating unit 11, but sepa-

rated from said end and socket 10 so as to provide vent and sight holes 15^b.

For use in connection with the above described apparatus I provide, as a new article of manufacture, a bar 17 of sealing wax weakened transversely at regular intervals throughout its length by grooves or depressions 18, and also having one side thereof formed with longitudinal serrations 19. The 10 grooves or depressions 18 provide relatively weak lines of cleavage distributed at regular intervals throughout the length of the bar, and it will be clear that by grasping one end of the bar in one hand and holding 15 the other portion of the bar with the other close to the end groove 18, a pellet of a predetermined and definite size can be broken off from the bar. This pellet, and each pellet section 20 of the bar, is designed to be 20 of just the right size to form a seal.

After breaking one of the pellets from bar 17 it is placed in position upon the envelope or the like to which the seal is to be applied and then the operator takes in 25 hand the apparatus or instrument shown in Fig. 1, pressing upon the button 13 so as to close the circuit 12 of heater unit 4. The instrument is then placed in position with relation to the pellet of wax resting on the 30 envelope so that the circular wall 15^a rests upon the envelope and surrounds the pellet with the heating unit 4 immediately above and out of contact with the latter and in heating proximity thereto. As soon as the 35 wax is melted the instrument is shifted so as to place the seal 8 upon the melted pellet, and the seal is pressed down in the usual fashion to make the impression upon the wax. It will be clear that not only is the 40 pellet heated and melted but the paper upon which the pellet rests is also heated thus establishing a stronger connection between the pellet and the paper than has been possible with the apparatus and means heretofore 45 provided.

When the instrument is placed in position with the wall 15^a surrounding the pellet and the heater 11 immediately above the latter, said wall serves to confine the heat in the 50 neighborhood of the pellet and to prevent air drafts, or air circulation, which would carry off the heat and prevent the same from reaching the pellet. Also the wall holds the document, paper, envelope or the like in a flat condition. The holes 15^b at the top of the wall 15^a not only provide outlets for the 55 escape of vapor or the like but they also provide sight holes through which the user of the instrument can watch the progress 60 of the heating operation. When the pellet has been heated to the desired extent smoke-like vapor will escape through the openings 65 15^b and serve as an indication to the user that the heating process has been carried far enough.

When the device is not in use for sealing purpose it may be set in an upright position with its legs 2 and 7 resting upon a table or other support. It will also be clear that the instrument may be used as a cigar 70 lighter as well as for applying seals.

In applying seals by the methods heretofore employed, the customary practice has been to apply a flame to the end of a wax bar and permit the wax to drop upon the 75 envelope or the like as it melts. The drops thus falling upon the envelope usually carried flame with them, were seldom accurately placed, and the amount of wax applied seldom accurately gauged. By this old 80 method it was almost impossible to produce a neat and attractive seal. Another objection was that the burning of the wax greatly discolored, and therefore disfigured, the same. Furthermore, it was impossible to 85 apply seals uniformly as regards the amount of wax employed for different seals.

Figures 8 and 9 illustrate an individual pellet of circular shape suitable for use with the above described apparatus. 90

When one of the pellets 20 from the bar 17 is used it is placed upon the envelope or the like with its serrated side uppermost and as will be clear, the serrations 19 provide much more heat absorbing surface than 95 would be provided by a flat or smooth side.

From the above description it will be seen that the wax is used in the form of pellets and, when one of these pellets is placed upon an envelope or the like, with the heating unit 100 in position immediately above, but out of contact with said pellet, the latter is heated and softened or melted by radiant heat from the heating unit. In this way the wax is heated and applied as a seal to the document 105 without the use of a flame or the application of a heated iron and just the amount of wax necessary to form the seal is employed.

What I claim is:

1. An instrument for use in applying sealing wax comprising a frame; an electric heating unit and a seal mounted on said frame relatively positioned so as to provide for convenient use thereof successively; a circuit including said heating unit and also 115 including circuit wires extending beyond said frame; a screw plug connected with said wires, and a wall carried by said frame surrounding said heating unit and adapted to be seated upon the envelope or the like to 120 which the seal is applied to support the heating unit at a predetermined distance above a wax pellet occupying a position upon the envelope or the like within said wall. 125

2. An instrument for use in applying sealing wax comprising a frame; an electric heating unit and a seal mounted on said frame positioned relatively on the latter so as to provide for convenient use thereof 130

successively; a circuit including said heating unit and also including circuit wires extending beyond said frame; a screw plug connected with said wires, and a wall carried by 5 said frame surrounding said heating unit and having openings at the upper end thereof, said wall serving to position the heating

unit with relation to the envelope or the like to which the seal is applied.

Signed by me at Boston, county of Suffolk and State of Massachusetts, this 6th day of January, 1927.

FREDERICK M. DURKEE.
